UNITED STATES PATENT OFFICE.

ERNEST STUART DANIELS, OF WEST POINT, VIRGINIA, ASSIGNOR TO JOHN ALEXANDER HUGH CAMERON, TRUSTEE, OF MONTREAL, CANADA.

PARQUET-FLOOR COMPOSITE SECTIONS.

Application filed March 13, 1925. Serial No. 15,271.

To all whom it may concern:

Be it known that I, ERNEST STUART DANIELS, a subject of the King of England, residing at West Point, in the county of 5 King William and State of Virginia, have invented certain new and useful Improvements in Parquet-Floor Composite Sections; and I do hereby declare the following to be a full, clear, and exact description of the 10 invention, such as will enable others skilled in the art to which it appertains to make and use the same.

This invention is designed as an improvement on the structure shown and described 15 in my co-pending application, Serial No. 15,270 filed Mar. 13, 1925, relating to floor and wall construction and more particularly to what is commonly known as parquetry flooring and wall panelling. The principal 20 object is to provide floor or wall panels constructed in composite sections having integral means for securing or joining a multiplicity of sections together in assembled cross-grain relation by interlocking tongue- 25 and-groove connections to form a solid floor or wall without necessity for other fastening means than said interlocking connections.

A further object is to provide rigid sections of the character referred to from 30 which durable parquetry floors, paneled walls and ceilings of attractive appearance, may be expediently, efficiently and economically constructed.

The invention will first be hereinafter 35 more particularly described with reference to the accompanying drawings which are to be taken as a part of this specification and then pointed out in the claims at the end of the description.

40 In said drawings, Fig. 1 is a perspective view of several sections or panels embodying this invention, which are joined in pairs and shown in relative position for interconnection or assembly with each other to form a 45 portion of a parquet floor, the several sections being substantially square in surface area;

Fig. 2 is a sectional elevation taken on the line 2—2 of Fig. 1;

50 Fig. 3 is a longitudinal side elevation of one of the composite sections;

Fig. 4 is a plan view of a single composite section, the means for rigidly holding its several pieces together being indicated in dotted lines; and

Fig. 5 is a perspective view of the preferred form of transverse splining rods or pins employed for compositely uniting the several pieces of a section together.

Referring to the drawings in which like reference numerals are used to indicate corresponding parts throughout the several views, 6 denotes the composite flooring sections, which as clearly shown in Figs. 1, 2 and 4, are individually formed of multiple 60 pieces of odd planking, boards or scrap material of equal lengths, united or secured together longitudinally in a composite structure with their edges and surfaces flush and the grain of the wood in the respective pieces 65 running in substantially the same direction, said pieces being united or secured rigidly together by means of transverse wooden or metal splining rods or pins 7 extending across substantially the full width of the 70 sections intermediate the ends thereof, said rods or pins being extendingly inserted in and through corresponding or registering holes or channels bored or drilled through the respective pieces of the sections transversely while the latter are held under lateral compression, said pins or rods being 75 preferably glue-coated in order to prevent loosening or withdrawal and hold the pieces of the sections more firmly in place as a 80 rigid structure.

These sections as illustrated, are formed with tenons 8 providing integral projecting tongues on opposite ends thereof, said tenons being preferably formed or cut on the 85 ends of the sections after the component parts thereof are united in a composite structure as set forth above, the outer edges along opposing sides of the sections being kerfed or grooved as at 9 to a standard 90 depth equal substantially to the width of the tenons on their ends, within which the extended tongues or tenons of similarly formed sections are adapted snugly to fit in interlocking engagement therewith. These 95 sections or panels may be formed in any desired size or shape (square, oblong or dia-

mond) and any suitable material may be utilized as the component parts thereof, the several pieces of each section being joined together in the manner described.

- 5 The section splining rods or pins may be uniform or smooth in contour, that is of the simpler form denoted by the numeral 7 in Figs. 1 to 4 inclusive, or grooved or notched at spaced intervals to provide a series of 10 peripheral undulations or crevices as shown in Fig. 5, in which a splining rod 10 of preferred form is illustrated, the grooves or notches therein forming pockets for the glue for more rigidly causing the rods to adhere 15 in place within the sections and hold the respective pieces thereof more firmly and positively together, the extremities of the rods terminating flush with the countersunk edges in the grooved sides of the sections, 20 in order that they may not extend into said grooves and prevent the tenons on correspondingly formed sections from complementarily and snugly fitting therein, with consequent gaps or spaces between contiguous edges of adjacent sections.

- It may here be noted that the component parts or pieces of the several sections or panels are first preferably united in a composite structure by means of the splining 30 rods or pins 7 or 10 above referred to, after which the outer edges of the outer pieces in each section are kerfed or grooved to provide longitudinal recesses or grooves in opposite sides thereof, and that the tenons are 35 thereafter formed or cut on opposing ends of the panels, thus providing composite sections which are interchangeably adapted to assembly in alternate cross-grain relation, by interlocking tongue-and-groove connections with each other.

- As indicated in Fig. 1, a multiplicity of similarly formed sections may be readily and quickly assembled by inter-engaging or interlocking tongue-and-groove connections 45 and cross-grain relation to each other in the manner described, to produce a solid, durable and attractive floor, wall or ceiling structure. If desired, edge or border-strips, of the form shown in my co-pending application hereinbefore mentioned, may be employed in order to facilitate the assembly and effect a somewhat neater and more attractive appearance to the completed floor. The sections or panels are secured in interlocking engagement with such edge or border-strips and with each other, by means 55 of the tenons which are fitted or pressed snugly within the opposing grooved edges of border-strip and sides of similarly formed sections. Where opposingly grooved edges 60 between sections, or between a section and a border-strip, are brought into meeting contact, removable splines of the character shown and described in my co-pending application referred to, may be employed to

provide extending loose tongues along the grooved side edges of the sections, but when the sections are laid edge to edge in cross-grain relation each to its adjacent sections, the removable splines need not be employed, 70 as the sections herein illustrated and described are designed for assembly without necessity for removable splines, nailing or other fastening means to each other.

The sections are thus assembled in connection with each other, each section being laid or arranged with the grain of the wood therein running at substantially right angles to the grain of the wood in its adjacent sections, the tenon or tenons on each section 80 being engaged in grooved edges along the sides of adjacent sections. It will be appreciated that any tendency of the wood to warp in the sections thus formed, will be effectually prevented by the individual 85 splining rods or pins 7 or 10, and the interlocking connections therebetween, in which the tenons of each section are effectually clamped in a "vise-like" manner within grooved edges of adjacent sections, thus 90 holding the same rigidly together in cooperative relation, so that the floor will not buckle nor shrink with spaces between sections, when the wood swells or shrinks, 95 causing unevenness or gaps in the floor.

In like manner, the sections may be utilized to construct a wall or ceiling, the tenoned ends of the sections being engageable within longitudinal grooves in the studing or joists of a building under construction. I desire it to be understood that the word "flooring" as used in the appended 100 claims, is intended to include not only flooring material, but wall panels, partitions, paneled ceiling and various other structures 105 in which my invention might be used.

Furthermore, in the broader aspects of the invention, other material than wood might be used to form similarly tongued and grooved sections or panels adapted to 110 perform the same functions as sections formed of wood, and I therefore do not wish to restrict my invention to parquetry floors or wall panels made entirely of wood, although the latter material is preferable.

An attractive and durable floor may be economically constructed with flooring section of the form described, in which heretofore waste products of lumber, such as short pieces of flooring material which are 120 usually cast off for fire-wood, may be economically utilized. Furthermore, hard but inexpensive wood which has been heretofore unfit for use as ordinary hard-wood flooring because of its tendency to split, and for such reason having a very low market value as compared with other woods, may be used in the sections without danger of the latter coming apart or loosening from place, upon splitting of the wood at any point.

Having thus described my invention, what I claim as new and desire to secure by Letters Patent of the United States is:

1. A parquet flooring comprising individually formed composite sections of flooring material inter-connected and held together in assembled relation by tongue and groove connections on their sides and ends with the grain of the wood in each section running substantially at right angles to the grain of the wood in adjacent sections, the tongues extending along opposite ends of the sections and the grooves extending along opposite sides thereof, the individual sections being composed of a plurality of wooden pieces of equal lengths placed edge to edge and having registering transverse holes therethrough intermediate the ends of the sections and transverse wooden binder rods forcibly inserted through said holes while said pieces are held together under lateral compression so as to form the sections in inseparable laterally compressed and adhesively bound composite structures with the grain of the wood in the several pieces running in substantially the same direction, the extremities of said rods and the tongues of each section terminating flush with the countersunk edges of the grooves in opposite sides thereof.
  2. A parquet flooring comprising individ-
- ually formed composite sections of flooring material inter-connected and held together in assembled relation by tongue and groove connections on their sides and ends with the grain of the wood in each section running substantially at right angles to the grain of the wood in adjacent sections, the tongues extending along opposite ends of the sections and the grooves extending along opposite sides thereof, the individual sections being composed of a plurality of wooden pieces of equal lengths placed edge to edge and having registering transverse holes therethrough intermediate the ends of the sections and transverse wooden binder rods coated with an adhesive substance and forcibly inserted through said holes while said pieces are held together under lateral compression so as to form the sections in inseparable laterally compressed and adhesively bound composite structures with the grain of the wood in the several pieces running in substantially the same direction, the extremities of said rods and the tongues of each section terminating flush with the countersunk edges of the grooves in opposite sides thereof.

In testimony whereof I affix my signature.

ERNEST STUART DANIELS.
